SHELL HOUSING FOR AN ELECTRIC LIGHTING FIXTURE

Oliver Lundquist, New York, N. Y., assignor to
Century Lighting, Inc., New York, N. Y., a cor-
poration of New York

Application January 22, 1949, Serial No. 386

Term of patent 14 years

(Cl. D48—15)

To all whom it may concern:

Be it known that I, Oliver Lundquist, a citizen of the United States, residing at the Borough of Manhattan, in the county of New York, and State of New York, have invented a new, original, and ornamental Design for a Shell Housing for an Electric Lighting Fixture, of which the following is a specification, reference being had to the accompanying drawing, forming part thereof.

In the drawing:

Fig. 1 is a front elevational view in half-section of a shell housing for an electric lighting fixture showing my new design;

Fig. 2 is a top plan view; and

Fig. 3 is a bottom plan view thereof.

I claim:

The ornamental design for a shell housing for an electric lighting fixture, substantially as shown.

OLIVER LUNDQUIST.
